(57) **CLAIM**

The ornamental design for an interproximal dental tool, as shown and described.

DESCRIPTION

FIG. 1 is a top, front, right side perspective view of the first embodiment of the interproximal dental tool, showing my new design;

FIG. 2 is a bottom, rear left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and

FIG. 8 is a right side elevational view thereof.

FIG. 9 is a top, front, right side perspective view of the second embodiment of the interproximal dental tool, showing my new design;

FIG. 10 is a bottom, rear left side perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a left side elevational view thereof; and,

FIG. 16 is a right side elevational view thereof.

The broken dash lines shown in the drawing views represent non-claimed subject matter, and neither the lines themselves nor anything within the lines form any part of the claimed invention.

1 Claim, 10 Drawing Sheets
